UNITED STATES PATENT OFFICE.

ROBERT A. MORRISON, OF PORTLAND, AND FRANKLIN L. OSWALD, OF GLADSTONE, OREGON.

FLATIRON STAND.

Application filed August 5, 1925. Serial No. 48,318.

To all whom it may concern:

Be it known that we, ROBERT A. MORRISON and FRANKLIN L. OSWALD, citizens of the United States of America, and residents of 5 Portland and Gladstone, respectively, county of Multnomah, and State of Oregon, have invented a new and useful Improvement in Flatiron Stands, of which the following is a specification.

10 The main objects of this invention are to provide an improved form of stand for supporting flat irons; to provide improved means for mounting the stand on an ironing board; and to provide a flat iron stand which 15 is collapsible so as to require a minimum amount of space when not in use.

An illustrative embodiment of this invention is shown in the accompanying drawing, wherein—

20 Fig. 1 is a side elevation of an ironing table to which an improved flat iron stand is attached, part of the supporting frame being omitted for clearness.

Fig. 2 is a top plan of the same, the stand 25 being shown in its extended position.

Fig. 3 is a top plan of the stand, the full lines showing the stand in its collapsed form and the dotted lines showing it extended, part of the ironing board being also shown 30 in dotted outline.

Figs. 4 and 5 are transverse sections taken respectively on the lines 4—4 and 5—5 of Fig. 3.

In the specific construction herein shown, 35 the invention is applied to an improved stand 1 mounted on the lower face of an ironing board 2, which is supported on a frame comprising upright legs 3 and inclined legs 4 pivotally secured to a bracket 40 5 and braced by braces 6 and 7 respectively.

The stand 1 is preferably made entirely of metal, such as iron, and in the form shown, it comprises a pair of substantially parallel spaced rails 8 which are slidably 45 supported in a pair of transversely disposed guideblocks 9 and 10 mounted on the lower face of the board 2. The block 9 is located at one end of the board 2 and the block 10 is spaced a short distance inwardly therefrom. A bar 11 extends transversely across the inner ends of the rails 8, and an upwardly projecting plate 12 extends across the outer ends thereof. As shown in Fig. 1, the outer ends of the rails 8 are offset from 50 the plane of the inner ends thereof so as to

provide a seat for lazy tongs 13. Supported on the rails 8 adjacent the outer ends thereof, is a plate 14 to which the outer end of the lazy tongs is secured by a pin 15.

Secured to the inner edge of the lazy tongs 60 13, is a bar 16 having a longitudinally extending slot 17 which slidably engages a pin 18 mounted on the lower face of the board 2. This pin and slot connection permits the collapsed lazy tongs to be moved 65 beyond the end of the ironing board before they commence to expand. The inner end of the bar 16 is adapted to abut against a shoulder 19 formed on the guideblock 10. Formed on the ends of the lazy tongs, are 70 upwardly projecting shoulders 20 which, together with the end plate 12, form an enclosure for a flat iron supported on the tongs.

In operation, when the ironing board is 75 not in use, the rails 8 occupy the position shown in full outline in Figs. 1 and 3 and the lazy tongs are collapsed so as to occupy a minimum amount of space between the end of the ironing board and the bracket 80 5. When it is desired to use the improved stand as a flat iron rest, the rails 8 are pulled outwardly so as to expand the lazy tongs as shown in full outline in Fig. 2 and in dotted outline in Fig. 3. 85

Although but one specific embodiment of this invention has been herein shown and described, it will be understood that certain specific details of the construction shown may be altered or omitted without departing from the spirit of this invention as defined by the following claims.

We claim:

1. A flat iron stand comprising a support, lazy tongs having means at one end 95 thereof for attachment to said support, the other end of said lazy tongs being adapted to be extended beyond said support to form a rest for a flat iron.

2. A flat iron stand comprising a pair 100 of substantially parallel spaced rails, means for slidably supporting said rails, lazy tongs supported on said rails and having one end thereof secured to said rails, and means for supporting the other end of said 105 lazy tongs.

3. A flat iron stand comprising a pair of substantially parallel spaced rails, means for slidably supporting said rails, lazy tongs supported on said rails and adapted 110

when extended to form a rest for a flat iron, parts projecting upwardly from said rails and tongs to form an enclosure for the iron, one end of said tongs being rigidly secured to said rails, and means for supporting the other end of said lazy tongs.

4. A flat iron stand comprising a support, a pair of substantially parallel spaced rails slidably mounted on the lower face of

5 said support and adapted to be projected beyond one end thereof, lazy tongs support-

ed on said rails and having the outer end thereof secured to the outer end of said rails, the inner end of said tongs being slidably connected to said support so as to be adapted for a limited movement longitudinally of said rails, said lazy tongs when extended forming a rest for a flat iron.

Signed at Portland, Oreg., this 28th day of July, 1925.

ROBERT A. MORRISON.
FRANKLIN L. OSWALD.
